United States Patent Office

Des. 186,591
Patented Nov. 10, 1959

186,591

CAR TOP CONTAINER

Eugene O. Clay, Los Angeles, Calif.

Application April 6, 1959, Serial No. 55,360

Term of patent 14 years

(Cl. D14—27)

FIG. 1.

FIG. 2.

FIG. 3.

FIG. 4.

FIG. 5.

Fig. 1 is a perspective view of the car top container embodying my new design;

Fig. 2 is a top plan view thereof;

Fig. 3 is a side elevational view of the container of this invention;

Fig. 4 is a front elevational view of the container; and

Fig. 5 is a rear elevational view of the container.

The broken line showing of an automobile is for purposes of illustration only.

I claim:

The ornamental design for a car top container, as shown and described.
